UNITED STATES PATENT OFFICE.

HENRY T. BRAGG, OF YONKERS, NEW YORK.

HOSE.

No. 884,634.

Specification of Letters Patent. Patented April 14, 1908.

Application filed February 15, 1906. Serial No. 301,143.

To all whom it may concern:

Be it known that I, HENRY T. BRAGG, a citizen of the United States, and resident of Yonkers, in the county of Westchester and State of New York, have invented a new and useful Improvement in Hose, of which the following is a specification.

The object of my present invention is to provide certain improvements in hose where-
10 by a continuous wrapping strip may be incorporated therein, the side portions of such strip being formed thinner than the intermediate portion thereof so that when the strip is wrapped around the hose, the thinner side portions of the strip which overlap each other will make up substantially the thickness of the intermediate portion whereby a continuous wrapper is formed of substantially the same thickness throughout.

15 A further object is to provide a hose of the above character in which the wrapping strip is formed of a flat knitted fabric the intermediate portion of which is closely knitted and the side portions are loosely knitted so that the results set forth may be accomplished, the wrapper at the same time permitting a hose to be made which will be very flexible and in which the liability of bursting under great strain is materially reduced.

20 It has been usual in making various kinds of hose which is formed in part of rubber, to use a woven fabric cut on the bias, the said fabric being wrapped around an inner rubber tube, the side portions and the ends of the bias strips being caused to overlap. This construction gives rise to an uneven wrapping of the hose in which leaks are frequently occurring owing to the fact that the bias strips must be necessarily short as they are 25 limited in length to the diagonal distance across a certain width of woven fabric.

In the accompanying drawing the illustration shows a section of hose with one layer of my improved wrapping strip applied thereto, the outer cover of the hose being broken away to more clearly show said wrapping strip in its position within the hose.

The inner tube of the hose is denoted by 1 and the outer tube is denoted by 2. The 30 wrapping strip which is shown in the present instance as comprising a single layer consists of a strip of flat knitted fabric the side portions 3 and 4 of which are knitted thinner than the intermediate portion 5. In the

method of winding shown in the accompany- 55 ing drawings, the thinner side portion 3 is caused to overlap the thinner side portion 4 as the strip is wound spirally along the hose, thus producing an even outer surface free from ridges, the overlapping side portions 3 60 and 4 together being of sufficient thickness to correspond with the thickness of the intermediate portion 5.

It is to be understood that the hose may have incorporated therein any number of 65 layers of my improved wrapping strip, the winding of one layer either being the reverse to the winding of another layer or in the same direction in staggered order for the purpose of breaking seams.

A hose constructed as herein described would be well adapted for high pressure work, such, for instance, as the air brake hose in railway service.

What I claim as my invention is:

1. A hose having a wrapping strip composed entirely of fabric incorporated therein comprising a thicker intermediate portion and thinner side portions, the side portions being overlapped to conform in thickness to 80 the thicker intermediate portion, thereby forming a continuous wrapper of substantially the same thickness throughout.

2. A hose having a wrapping strip of knitted fabric incorporated therein comprising a 85 closely knitted intermediate portion and loosely knitted side portions, the side portions being overlapped to conform in thickness to the thicker intermediate portion thereby forming a continuous wrapper of substan- 90 tially the same thickness throughout.

3. A hose having a wrapping strip of flat knitted fabric comprising a closely knitted intermediate portion and loosely knitted side portions, the side portions being overlapped 95 to conform in thickness to the thicker intermediate portion thereby forming a continuous wrapper of substantially the same thickness throughout.

In testimony, that I claim the foregoing as 100 my invention I have signed my name in presence of two witnesses, this 10th day of February 1906.

HENRY T. BRAGG.
